UNITED STATES PATENT OFFICE.

CLARENCE M. HILL, OF WILKINSBURG, PENNSYLVANIA, ASSIGNOR OF ONE-HALF TO
DONATO D'ARCANGELO, OF VERONA, PENNSYLVANIA.

SANDING DEVICE.

Application filed January 4, 1927. Serial No. 158,888.

This invention relates to motor vehicles and more particularly to a sanding device adapted to deposit sand or the like beneath the wheels of a vehicle for the purpose of 5 increasing the traction of the wheels on the ground so as to prevent skidding.

Various arrangements have heretofore been attempted for accomplishing this function but such devices have failed because 10 they have followed, more or less, the arrangement of sanding devices employed on street cars, and the like and have been of such construction as to merely drop a charge or stream of material on the ground directly in front of the rear wheels of the associated vehicle. In view of the fact that the 15 majority of skids are in the form of lateral sliding movements, it will be apparent that any arrangement for depositing an anti-skid material in front of a wheel sliding laterally 20 is useless.

An object of this invention is to provide a device of the type set forth of such construction and arrangement that the anti-skidding material will be positioned so as 25 to prevent or stop a skid irrespective of its direction.

A further object is to provide a sanding device for vehicles of such arrangement and 30 construction that the sand or other material will be forcibly positioned beneath the associated wheels irrespective of the direction of movement thereof.

A still further object is to provide a device 35 capable of accomplishing the result set forth of such arrangement as to be easy and cheap to manufacture and assemble and positive and reliable in operation.

These and other objects which will be apparent to those skilled in this particular art are accomplished by means of the invention illustrated in the accompanying drawings in which Figure 1 is a somewhat diagrammatic view showing in elevation one embodiment 45 of this invention. Fig. 2 is a similar view showing the arrangement of Fig. 1 in plan. Fig. 3 is a longitudinal sectional view through a portion of the device illustrated in Figs. 1 and 2 and Fig. 4 is a partial transverse section on the line 4—4 of Fig. 3.

The particular embodiment of this invention which has been chosen for the purposes of illustration includes a hopper or con-

tainer for holding any desired amount of anti-skidding material, such, for example, as sand or the like.

The hopper is provided with an opening in the bottom and an ejector or sand throwing device is associated with the hopper in such a way as to be movable into position for receiving sand through the hopper opening. Mechanism is associated with the ejector for the purpose of actuating it in such a way as to forcibly expel the charge of material therefrom and spread the same over a substantial area of ground immediately around an adjacent wheel so that at least some of the material will be in the path thereof irrespective of the direction in which it may skid.

Figs. 1 and 2 illustrate the invention as of double form wherein a double hopper has two spreaders or ejectors associated therewith for the purpose of simultaneously throwing the sand from the hopper outwardly on both sides in order that both the adjacent wheels of the vehicle will be prevented from skidding. It will, of course, be understood that the invention may be embodied in a single hopper or ejector or constructed in any other desired form as far as this feature is concerned.

As illustrated, the invention includes a hopper 5 adapted to contain any desired amount of sand or any other anti-skidding material. The hopper preferably has an inclined bottom 6 and an outlet opening 7 is formed in the bottom at its lowest point. A sand spreader or ejector 8 is mounted for sliding movement beneath the bottom of the hopper and the top of the ejector is provided with an opening 9 for permitting the ejector to be filled with material when retracted to its rearmost position in which the opening 9 in the top of the ejector registers with the discharge opening 7 in the hopper bottom. It will be apparent that in all other positions the top of the ejector will form a closure for preventing the loss of material through the discharge outlet. The ejector is provided with grooves 10 adjacent its upper edge on each side for receiving track forming, supporting ledges 11 provided along the bottom of the hopper. The front of the hopper is provided with a door 12 mounted for horizontal swinging movement upon a

shaft 13 and adapted to be normally held in closed position by a door closing spring 14.

Ejector operating springs 15 are associated with the ejector in such a way as to normally pull the latter forwardly into sand discharging position.

The hopper is designed to be positioned beneath the floor board or similar structure of a motor vehicle and each ejector has an operating cord 16 secured to the rear thereof and extending around guiding pulleys 17 to a single operating cord conveniently positioned within reach of the operator of the vehicle, through which mechanism the operator is able to draw the sand ejector rearwardly against the tension of the operating springs 15 until the sand in the hopper can flow through the aligned openings 7 and 9 into the ejector. Release of the operating cord 16 permits the springs 15 to return the sliding ejector suddenly and forcibly to its original position. A door operating stop 18 is adapted to strike an upwardly projecting tongue 19 upon forcible return to the ejector under the influence of the actuator springs so that the door flies open and the sand or other anti-skidding material is forcibly thrown from the ejector laterally, and driven under and around the adjacent wheel. By this lateral throwing of the material, as distinguished from merely dropping it on the ground or track, it is spread around on all sides of the adjacent wheel instead of merely in front thereof and a part is thrown directly beneath such wheel. The operating springs 15 are so arranged that if, instead of suddenly releasing the ejector cord 16, the operator does so slowly so that the ejector is not suddenly and forcibly returned to its original position by the springs 15, the stop 18 will not strike the door operating tongue 19 with sufficient force to open the same and the sand in the ejector will not be discharged.

45 What I claim as new and desire to secure by Letters Patent is:

1. The combination in a vehicle sanding device of a hopper having an outlet, an ejector slidably mounted in operative relation thereto and provided with an opening adapted to register with said outlet, means for moving said ejector so as to register said openings and means for forcibly returning said ejector to its original position so as to cause a charge of sand to be thrown therefrom.

2. The combination in a vehicle sanding device of a hopper, an ejector, and means for operating said ejector so as to cause a charge of material received from said hopper to be forcibly expelled therefrom.

3. The combination in a vehicle sanding device of a hopper, an ejector, means for moving said ejector into position to receive

material from said hopper and means for operating said ejector so as to forcibly expel material therefrom.

4. The combination in a sanding device including a hopper of an ejector slidably associated therewith and adapted to be moved to material receiving position in relation thereto, a door normally closing one end of said ejector to prevent the loss of material therefrom, a door trip operated by the forcible return of said ejector for opening said door and spring means for so operating said ejector as to cause said trip to open said door to permit the discharge of the material therethrough.

5. The combination in a sanding device including a hopper of an ejector slidably associated therewith and adapted to be moved to material receiving position in relation thereto, a door normally closing one end of said ejector to prevent the loss of material therefrom, a door trip operated by the forcible return of said ejector for opening said door, spring means for so operating said ejector as to cause said trip to open said door to permit the discharge of the material therethrough and means for normally maintaining said door closed.

6. The combination in a vehicle sanding device of a hopper adapted to hold a quantity of anti-skidding material, a spreader associated with said hopper so as to receive material therefrom and mechanism for operating said spreader so as to forcibly expel material therefrom in a lateral direction.

7. The combination in a sanding device of a hopper, a spreader provided with an opening, means for supplying material to said spreader from said hopper and means for forcibly shifting said spreader so as to throw said material through said opening.

8. The combination in a sanding device of a hopper, a movable spreader associated therewith for receiving material therefrom and provided with a discharge opening, a stop for limiting the movement of said spreader in one direction and means for driving said spreader against said stop so as to expel said material through said opening.

9. The combination in a sanding device of a hopper, a movable spreader associated therewith so as to receive material therefrom and provided with a discharge opening, a stop for limiting the movement of said spreader in one direction and resilient means for forcibly shifting said spreader into engagement with said stop so as to expel said material through said opening.

In testimony whereof, I have hereunto subscribed my name this 3rd day of January, 1927.

CLARENCE M. HILL.
